Specification for Design.

Patented Feb. 10, 1920.

Application filed August 6, 1919. Serial No. 315,769. Term of patent 14 years.

To all whom it may concern:

Be it known that I, FREDERICK W. LOHR, a citizen of the United States, residing at New York, N. Y., have invented a new, original, and ornamental Design for Signal-Casings, of which the following is a specification, reference being had to the accompanying drawing, forming part thereof.

In the drawing, Figure 1 is a perspective view, Fig. 2 is a front elevation, and Fig. 3 is an end elevation, of a signal casing, showing my new design.

I claim:

The ornamental design for a signal casing, as shown, or its equivalent.

FREDERICK W. LOHR.
